UNITED STATES PATENT OFFICE.

JOSEPH DUX, OF CHICAGO, ILLINOIS, ASSIGNOR TO THE CAXTON COMPANY,
OF CHICAGO, ILLINOIS, A CORPORATION OF ILLINOIS.

DESIGN FOR A DESK AND SEAT SUPPORT OR STANDARD.

SPECIFICATION forming part of Design No. 36,506, dated August 18, 1903.

Application filed June 25, 1903. Serial No. 163,151. Term of patent 14 years.

To all whom it may concern:

Be it known that I, JOSEPH DUX, a citizen
of the United States, residing at Chicago, in
the county of Cook and State of Illinois, have
5 invented a new, original, and ornamental De-
sign for a Desk and Seat Support or Standard,
of which the following is a specification, refer-
ence being had to the accompanying drawing,
forming a part thereof.

10 The figure is a side elevation of my new
design for standard or support for desk and
seat.

What I claim, and desire to secure by Let-
ters Patent, is—

The ornamental design for a desk and seat 15
support or standard as shown.

In testimony whereof I have signed my
name to this specification in the presence of
two subscribing witnesses.

JOSEPH DUX.
